[57] CLAIM

The ornamental design for a hand engageable cardio-pulmonary resuscitative device or the like, substantially as shown and described.

DESCRIPTION

FIG. 1 is a front elevation of a hand engageable cardio-pulmonary resuscitative device or the like, showing my new design;

FIG. 2 is a side elevation thereof;

FIG. 3 is a top plan view thereof;

FIG. 4 is a bottom plan view of the embodiment of the device illustrated in FIGS. 1 and 3;

FIG. 5 is a bottom plan view of the modified embodiment of the device illustrated in FIGS. 1 and 3; and

FIG. 6 is a front elevation thereof.
